(57) **CLAIM**

The ornamental design for a marine trash receptacle, as shown and described.

DESCRIPTION

FIG. 1 is a perspective view of an embodiment of a marine trash receptacle showing my new design.

FIG. 2 is a top plan view of the marine trash receptacle of FIG. 1.

FIG. 3 is a bottom plan view of the marine trash receptacle of FIG. 1.

FIG. 4 is a right side elevational view of the marine trash receptacle of FIG. 1.

FIG. 5 is a left side elevational view of the marine trash receptacle of FIG. 1.

FIG. 6 is a front elevation view of the marine trash receptacle of FIG. 1.

FIG. 7 is a rear elevation view of the marine trash receptacle of FIG. 1; and,

FIG. 8 is a perspective view of a marine trash receptacle of FIG. 1 in a collapsed condition.

The broken lines shown in the figures are included for the purpose of illustrating environment and forms no part of the claimed design.

1 Claim, 8 Drawing Sheets
